UNITED STATES PATENT OFFICE.

ANTONIO MISTRETTA, OF NEW YORK, N. Y.

TRIMMING DEVICE FOR SEWING-MACHINE ATTACHMENTS.

Application filed June 16, 1926. Serial No. 116,381.

This invention relates to improvements in trimming attachments for embroidery sewing machines especially adapted for use in connection with machines of the Bonnaz type for producing appliquéd embroidery; and its primary object is to provide certain improvements in the construction of the trimming device proper, usually forming part of such attachments in order to improve and facilitate its operation; said trimming device being in the nature of a scissor-like implement of the type described and claimed by me in two other patent applications, entitled "Trimming attachment for embroidery machines", filed October 3d, 1925, Serial No. 60,263, and "Trimming device for embroidery machines" filed February 19th, 1926, Serial No. 89,465, respectively.

Another object is to provide a trimming device of the character mentioned, which, owing to a special construction of its lower blade will not interfere with or hamper either the feeding of the cloth while the work is progressing, or the displacement of the trimming device in relation to the fabric transversely of the stitching line when changing the direction of said stitching line.

Other objects and advantages of the present invention will more fully appear as the description proceeds and will be set forth and claimed in the appended claims.

The invention relates to improvements in a mechanically operated trimming device which is capable of being turned about its axis in any direction required in order to follow a pattern or outline, together with a needle bar capable of such movements under the control of the operator.

The device is particularly designed for cutting out figures from fabrics parallel to a stitch which follows a certain predetermined outline by virtue of an arrangement whereby the trimming and stitching are effected simultaneously through the cooperation of its various elements.

By appliquéd or Bonnaz embroidery is meant that kind of work where a piece or panel of decorative fabric is attached to a base fabric by means of a stitch which follows a certain predetermined outline representing some object or flower or animal, or some other decorative motif or design.

After the panel or appliquéd work proper has become attached to the base fabric by means of the stitching, the same is trimmed all around the stitching leaving a relatively

small margin, so that due to the difference in the color or texture of the materials forming the panel part and the base fabric, many novel and artistic effects may be obtained.

The work is generally carried out in two distinct steps, the first step being that of stitching the two pieces together following the design which may have been previously printed on the panel part and the other step being the trimming of the same which is generally performed by hand by means of ordinary scissors. This trimming operation is therefore, necessarily slow, due to the care which must be exerted in order to keep the width of the margin uniform, and the work being largely dependent upon the ability of the operator to correctly gauge the width of the margin all around, the result is not always all that could be desired.

In my application No. 60,263, above referred to, I have described a device comprising a scissor-like implement having a stationary blade and a movable blade, the movable blade being operated by a member which is attached to the needle bar and which therefore follows both the axial and the angular movements of the needle bar. Said member transmits the axial movements of the needle bar to the movable blade by means of an articulated connection and the angular movements of said bar to the cutting device as a whole so that the shearing line is always set parallel to the stitching line.

In operating the said device, I have found it desirable to modify the same in its various details in order to obtain better results and a more reliable operation, and in my subsequent application No. 89,465, I have described a similar device by means of which improved results may be obtained due to two improvements introduced in the same. One of these two improvements consists in so constructing the trimming device that the oscillating blade is the inner blade while the stationary blade is the outer blade, so that the progress of that part of the work which remains attached to the base fabric is not hampered; and another improvement consists in bending the outer end of the stationary blade to one side in order to provide a transversal tract, offering an efficient support for the fabric to be cut by the device, assisting the feeding action of the presser foot.

The present invention more especially re-

fers to a further improvement in the construction of the stationary blade, the object of said improvement being to obviate certain difficulties which have been encountered 5 in the operation of the device, when certain kinds of cloth are used; and in describing the device in its present form, I will point out in detail the feature which has thus been improved by referring to the previous arrangement.

In the annexed drawings—

Fig. 1 is a side view in elevation of my trimming attachment as applied to an embroidery machine;

15 Fig. 2 is a front view in elevation of the same;

Fig. 3 is a rear view in elevation of the same;

20 Fig. 4 is a side view in elevation of the same with the needle bar in its lower position;

Fig. 5 is a detail plan sectional view through line 5—5 of Fig. 1;

Fig. 6 is a detail plan sectional view through line 6—6 of Fig. 4;

25 Fig. 7 is a detail plan sectional view through line 7—7 of Fig. 1;

Fig. 8 is a fragmentary plan view of the trimming device proper in operation in its preferred form;

30 Fig. 9 is a detail plan view of the stationary blade used in my previous application, No. 89,465, illustrating one of the difficulties which may hinder its operation when an open mesh fabric is used; and

35 Fig. 10 is a detail plan view of the trimming device in another modified form, illustrating another way of avoiding said difficulty, adapted for use in some special cases.

Referring to Figs. 1 and 2, and 3, 10 designates the needle bar which is represented at 40 the highest point of its reciprocating travel, at which point its lower end 11 still projects beyond the lower end of needle bar casing 12. 13 designates a collar integral with a gear 14, which is an integral part of the equipment of the Cornely type of machine; said gear is restrained from axial movement by a retaining forked member 15 inserted in 45 a groove 16, but is free to rotate around needle bar casing 12, upon which said collar is inserted. Said collar is therefore made use of for attaching the trimming attachment proper so as to render said attachment free to rotate with the needle bar, about its axis.

50 55 The trimming attachment proper consists of a stationary blade 17 which is carried by a vertical stem 18 depending from collar 13, said stem being secured to said collar by means of a clamping member 19, provided 60 with lateral extensions 20, 21, attached to collar 13 by means of screws 22.

Clamping member 19 has a longitudinal opening adapted to receive the upper end of stem 18, so that said stem may be adjusted to 65 and from the bed plate of the machine 23 and

can then be clamped in position by means of screws 24. This arrangement therefore renders the device adjustable for different thicknesses of cloth, the base material upon which the appliquéd work is attached by stitching 70 passing between the stationary blade 17 and the bed plate 23.

The movable blade designated by 25 is pivotally mounted at 26 upon the lower end 27 of stem 18, with its cutting edge abutting 75 against the cutting edge of blade 17; so that the two blades together form a scissor-like trimming contrivance adapted to trim the appliquéd part of the work quite close to the needle 28 and at a uniform distance from the 80 stitch produced thereby.

The movable blade is caused to oscillate around its pivot by utilizing the reciprocating axial motion of the needle bar. To this end, an upwardly extending member 28 is 85 secured to the lower portion 11 of the needle bar by means of a screw 29 or in any other suitable manner. The upper part 30 of said upwardly extending member is connected to the upper end 31 of the movable blade by 90 means of an articulated connection 32, so that the up and down motion of the needle bar will cause oscillating motion of said blade 25.

The upwardly extending member 28 has a vertical opening 33 through which passes 95 stem 18, which is thus maintained in its vertical position. Due to this arrangement it will be observed that the angular movements of the needle bar, which are shared by member 28 connected thereto, will be transmitted 100 by said member 28 to stem 18 which is guided thereby, causing the collar 13 to participate in said angular movements. In order to insure a sharp cutting action, I provide a spring 105 34 attached at 35 to the upper part 30 of member 28, said spring forcing connection 32 outwardly and maintaining therefore blade 25 in close adherence to blade 17; this action being comparable to the side pressure of one 110 blade against the other, which is exerted by hand when using an ordinary pair of scissors.

The arrangement described causes the cutting device to be operated simultaneously 115 with the needle bar and also causes the same to follow the angular displacements of the needle bar. Furthermore, by mounting the stationary blade so that the same is detached from the bed plate of the machine and is vertically adjustable in relation thereto, it is 120 possible to trim only one of the fabrics employed in producing the work while the other fabric remains intact. This is particularly important in connection with appliquéd work since, as stated, only the appliquéd or panel 125 part should be trimmed while the base material should be left untouched.

The material is fed to the needle bar by means of a presser foot 36, associated with the needle bar and movable angularly there- 130

with, said presser foot moving inwardly each time a stitch is produced in order to feed the fabric for the next stitch.

In Fig. 4 where the device is shown in operation, applied to the production of appliqué work, it will be observed that the presser foot is shown in its inward position after the feeding action, its original position being shown in Fig. 1 where said foot is co-axial with the needle.

The pivotal connection between the two blades is somewhat to the rear of the needle, thus permitting of their cutting or operative portion being located exactly in correspondence of the needle itself; by virtue of this arrangement the cutting operation always takes place at a point located on a line at right angle to the direction of the stitching at the point where the stitching takes place.

It will be observed that the lower edge of the stationary blade is parallel to the upper surface of the bed plate of the machine, in order to provide a suitable adjustable clearance space for the fabric passing there-through. It will also be observed that the stationary blade is very narrow and elongated in form, so that the cloth is only slightly raised by the insertion of said stationary blade between the base material and the panel material.

It will furthermore be observed that the movable blade abuts against the inner face of the stationary blade, so that the inner part of the fabric which is cut and which is closely held by the base fabric due to the stitching can freely run underneath the movable blade, no stretching effect being produced on said fabric. Due to this arrangement, the cutting device may be set extremely close to the needle, and this is an advantage because the margin around the stitch should be as narrow as possible.

The lower or stationary blade which is preferably very narrow so as not to unduly stretch the cloth, is preferably made detachable from the stem, so that a new blade may be quickly inserted in position when the old blade is worn out.

Close adherence of the movable to the stationary blade is obtained by means of a spring 34, the action of which is such as to force the movable blade outwardly, against the stationary blade. Said spring is made of a piece of steel wire which is permanently attached at one end to member 28, by means of a screw 35.

In the device described in my application No. 89,465, I have pointed out the advantage of bending to one side the outer end of the stationary blade as shown at 37 in Fig. 9; this bend being provided in order to afford an efficient support for the fabric to be cut by the device, so as to assist the feeding action of the presser foot.

This transversal tract also facilitates the

work in that it positively prevents the possibility of the blade sliding out of position from underneath the fabric; it also assists in maintaining the fabric to be cut at right angle to the cutting edges so that a sharp cutting action is obtained thereby.

By shifting the movable blade to the inner position, it becomes advantageous to insure a condition where its outer end does not reach the stationary or lower blade even when the movable blade is at the extreme end of its downward travel, as shown in Fig. 4; this making it possible to connect the lower end of connection 32 to the outer face of the movable blade by means of a pivot 38, without the possibility of interference by the lower or stationary blade.

However, in operating this type of blade, I have found that its laterally bent end portion frequently interferes with the progress of the work when an open mesh fabric is used for producing the work. This interference with the progress of the work is likely to occur when the trimming device is angularly moved about its axis together with the needle bar in order to produce a bend in the trimming when required by the outline of the embroidery design; more particularly some difficulty is likely to arise when the trimming device is turned in the direction of the bent portion of the blade as indicated by the arrow in Fig. 9.

In this case, the pointed end of the bent portion of the blade may easily penetrate between the meshes of the fabric, as the drawing shows, and the fabric must then be disengaged from the blade before the work can be proceeded with.

Open mesh fabrics such as shown, known as nets, are very frequently used in this class of work and therefore the operation of the device is seriously hampered in such uses; I have therefore further improved my device by bending the free end of the stationary blade laterally to form a transversal tract 39 and then inwardly to form a longitudinal tract 40, as shown in Figs. 7 and 8.

In this manner any movement of the trimming device transversely of the stitching line will cause a longitudinal tract of blade to abut against the fabric during the movement in either direction, instead of a point which might easily become enmeshed in the open work of the fabric itself. The possibility of such an occurrence is thus positively prevented, both if the trimming device is displaced towards or away from the direction of the stitch line.

The same arrangement may, of course, be adopted where the trimming device and the needle bar are not rotatable about their common axis, but the fabric is displaced instead according to the design to be produced; in this case also, a continuous tract of blade is in the path of the fabric instead of a point, whether the fabric is fed longitudinally of the

trimming line in the normal way or whether the fabric is displaced transversely of the trimming line in either direction.

It is obvious that the free end of the stationary blade could also be bent in a curve instead of being bent to form a transversal and a longitudinal tract; provided the free end of the curve is directed transversely to the possible direction of movement of the fabric, or to the direction of displacement of the cutting edges of the trimming device, when a bend in the trimming is produced, and is directed away from the fabric when said fabric is fed in a straight line in a normal direction.

15 Therefore, such a curved bend should be well extended inwardly so as to prevent the possibility of its pointed end penetrating the meshes of the fabric when the fabric is not moved strictly in the direction of the cutting edges of the blades, but is rotated about the cutting point of the trimming device as a pivot, or when the trimming device itself is displaced around its axis as previously described.

25 This is equivalent to saying that the extreme end of the stationary blade must be directed at an angle to and preferably inwardly of a line outwardly extending from said extreme end tangential to a circumference passing through said extreme end having for its center, the center of rotation of the cutting device or of the fabric as the case may be. The angle at which the extreme end of the blade is directed in relation to said tangential line should be fairly wide in order to effectively avoid the possibility of said free end becoming entangled in the meshes of the fabric.

It is possible, of course, that for the production of certain designs, the fabric or the trimming device may have to be turned in one direction only; this is true for instance in the cutting of a circular, or oval, or rectangular outline, where there are no recesses in the outline requiring occasional turnings in the opposite direction. In this case, it is sufficient to bend the blade laterally only in one direction, which when the trimming device is to the right of the needle, is the outward direction as shown at 41, in Fig. 10; because if the fabric is 40 the element which is displaced the same only has to be turned in a counter clockwise direction, and the free end of the stationary blade being bent away from the fabric, that is, in the direction of the lateral feed of the fabric 45 when turning, there is no danger of the point penetrating between the meshes, a continuous tract of blade and not a pointed end being now in the path of the fabric's travel.

The same remarks apply if the trimming device is the movable element, in which case the trimming device will have to be moved in a clockwise direction as the arrow in Fig. 10 indicates.

By virtue of this arrangement, the device becomes adapted for use in connection with

fabrics of all kinds and weaves, including open mesh fabrics, and therefore, its efficiency and its field of application are considerably increased.

I claim:

1. In a sewing machine, the combination with a needle bar capable of axial reciprocating motion, of a trimming device co-acting therewith, comprising a stationary and a movable blade, said stationary blade having its free end bent reversely of said blade so that if either the fabric or the trimming device is displaced one way or the other transversely of the direction of the stitch in order to change said direction, the contact between the blade and fabric is established through a continuous tract of blade transversely to the direction of said displacement. 70

2. In a device of the class described, the combination with a movable blade, of a stationary blade insertable underneath the fabric to be trimmed by said device, said stationary blade having its free end bent laterally and reversely of said blade in order to present a tract directed transversely to the direction of movement when either the fabric or the trimming device is moved transversely to the direction of the stitch. 85

3. In a device of the class described, the combination with a movable blade, of a stationary blade insertable underneath the fabric to be trimmed by said device, said stationary blade having its free end bent laterally to form a transversal tract, and then inwardly to form a longitudinal tract substantially parallel to the cutting edge of the said device. 95

4. In a machine of the character specified, the combination with a needle bar capable of axial reciprocating motion and capable of angular movement about its own axis, and an axially stationary member coaxial and adapted to rotate with said needle bar, of a trimming device having a movable blade operatively associated with said needle bar, and a stationary blade mounted on said member adapted to be inserted underneath the fabric to be trimmed by said device, said stationary blade having its free end bent reversely of said blade so as to present a continuous tract 105 directed transversely to the direction of the movement when said fabric is fed longitudinally of the cutting edge or when the trimming device is angularly displaced in either direction together with the needle bar about 110 their common axis. 115

5. In a machine of the character specified, the combination with a needle bar capable of axial reciprocating motion and capable of angular movement about its own axis, and an axially stationary member coaxial and adapted to rotate with said needle bar, of a trimming device having a movable blade operatively associated with said needle bar, and a stationary blade mounted on said member 125 130

adapted to be inserted underneath the fabric to be trimmed by said device, said stationary blade having its free end bent laterally to form a transversal tract and then inwardly 5 to form a longitudinal tract substantially parallel to the cutting edge of said blade.

6. In a machine of the character specified, the combination with a needle bar capable of axial reciprocating motion and capable of 10 angular movement about its own axis, and an axially stationary member coaxial and adapt-

ed to rotate with said needle bar, of a trimming device having a movable blade operatively associated with said needle bar, and a stationary blade mounted on said member 15 adapted to be inserted underneath the fabric to be trimmed by said device, said stationary blade having its free end bent laterally and inwardly of said blade and being directed inwardly of a line outwardly extending from 20 said end, tangentially of its path of travel.

ANTONIO MISTRETTA.
